Primary Examiner — Cynthia R Underwood(74) *Attorney, Agent, or Firm* — McAndrews, Held & Malloy, Ltd.(57) **CLAIM**

The ornamental design for a container for wire, as shown and described.

DESCRIPTION

FIG. 1 is a top perspective view of a container for wire showing our new design in which an access door is in a closed position;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top perspective view thereof, showing an access door in an open position.

The broken lines in the figures illustrate portions of the container that form no part of the claimed design.
